UNITED STATES PATENT OFFICE

JAMES ALVAH CREELMAN, OF CHICAGO, ILLINOIS

SHOE LAST FOR THE CORRECTION OF CERTAIN AILMENTS OF THE HUMAN FOOT

Application filed July 29, 1927. Serial No. 209,376.

This invention relates to lasts for use in making shoes to be worn as correctives of and relief of ailments to which the human foot is subject, such as fallen or weakened metatarsal 5 arches and weak, fallen, flexible or flat longitudinal arches.

An object of the invention is to provide an improved shoe last for the purpose mentioned having its bottom of novel configuration comprising recessed and inclined portions designed and adapted to receive inserts and wedges to be placed under the insole of the shoe and located rearwardly of the heads of the metatarsal bones and forwardly from 15 part of the heel bones of the foot for which the shoe is intended.

Another object of the invention is to provide an improved shoe last embodying the novel construction and capable of the advantageous uses of the shoe last herein disclosed, reference being made to the accompanying drawing in which

Fig. 1 is an under side view of my improved last having the shoe insert element thereon.

Fig. 2 is a side elevation of the last with part in section.

Figs. 3 and 4 are cross sectional views on the lines 3—3 and 4—4, respectively, of Fig. 2.

Fig. 5 is a top plan view of the insert wedge 30 element.

Fig. 6 is a side edge elevation of the insert wedge element.

The last shown comprises a heel portion 1 and a front portion 2 held in proper cooperative relationship by a pivotal connection 3.

I modify the under side of this last from usual or standard construction by forming in the front portion 2 of the last a recess 4 which is concave in cross section and which continues through a shallow centrally disposed channel 5 to a beveled surface 6 inclining upwardly and forwardly from near the rear outer corner of the last to intersection with the inner side. This beveled surface is formed in the under side of the heel portion of the shoe at an inclination of about 35°, more or less. The said beveled surface may be extended on the under side of the front portion of the last if desired, as will be readily understood by reference to Fig. 2 of the drawing.

The beveled surface 6 begins near the rear end of the heel portion 1 of the last and becomes more pronounced toward the front end of the heel portion of the last. That is to say, there is very slight bevel at the rear end of the heel portion and in side elevation of the last the intersection of the bevel with the inner side of the last is arcuate, as clearly shown in Fig. 2 of the drawing. The arcuate bevel is extended on the under side of the rear end of 55 the front portion of the last as shown in connection with the shallow centrally disposed channel 5.

This novel configuration of the under side of the last is designed and adapted to receive an insert device, as shown. The insert device shown comprises a section of material including a relatively wide front end portion 7 and a wide rear end portion 8, said front and rear portions being connected by a comparatively narrow portion 9. The front portion 7 is thickened by a section 10 of pliable material to fill the recess 4 and thereby provide a raised insert in the sole of the shoe slightly posterior to the heads of the metatarsal bones so as to support and correct a flattened or weakened metatarsal arch. And a wedge 11 of pliable material is attached to the rear portion 8 and fills the beveled area 6; while the longitudinally relatively narrow and thin 70 portion 9 fills the relatively narrow longitudinal grooved portion 5 of the last. In this way weak, fallen, flexible or flat longitudinal arches are corrected and relieved by the same insert and wedge device which affords relief 75 80 85 for the fallen or weakened metatarsal arch.

In the manufacture of the shoe the insole may be placed on or under the insert and wedge device described in a manner to afford maximum ease and comfort to the wearer.

It is apparent that the invention may be varied within equivalent limits as to dimensions without departure from the nature and principle thereof.

Accordingly, I do not restrict myself in these or other unessential particulars, but what I claim and desire to secure by Letters Patent is:

1. A last having the under side of the heel portion inclining upwardly in an arcuate 100

bevel from near the outer side to intersection with the inner side of said heel portion and being of greater upward incline toward the front end of the heel portion, and having a 5 concave recess in the under side of the front portion thereof posterior to the heads of the metatarsal bones of the foot for which a shoe made on the last is intended.

2. A shoe last having a concavity in the under side thereof rearwardly of the plane of 10 the heads of the metatarsal bones of a human foot for which the last is designed for use in making shoes and having the under side of its heel portion inclined upwardly from near the 15 outer side to intersection with the inner side in advance of the rear end of the last, the upward inclination at the under side of said heel portion increasing from near the rear end of said heel portion forwardly.
